POWER OPERATED TONE CONTROL MECHANISM

Filed Sept. 2, 1925

Patented Apr. 3, 1928.

UNITED STATES PATENT OFFICE.

JOHN HAYS HAMMOND, JR., OF GLOUCESTER, MASSACHUSETTS.

POWER-OPERATED TONE-CONTROL MECHANISM.

Application filed September 2, 1925. Serial No. 54,078.

This invention relates to musical instruments of the percussive type and more particularly to improvements in the control of tone quality and musical dynamics of musical sound produced by such instruments.

It is one object of the present invention to provide an improved stringed musical instrument of the percussive type having means for variably controlling the amount of musical sound emitted from the instrument and an improved control device therefor.

The invention has particular reference to improved means of controlling the volume of sound which may readily be actuated by the musician with a minimum of effort on his part.

The invention has especial adaptability for use in a piano in which the percussive mechanism is employed for vibrating a string and relates particularly to the use of an improved mechanism for controlling the volume of sound emitted from the instrument and to means for modifying the action of the sound control means at the will of the operator.

A feature of the invention is the provision of a separate source of power for actuating the tone modulators or reflectors so that the musician is relieved of the mechanical effort of operating the reflectors directly and may devote his attention to imparting the desired expression to the music.

Other objects will appear from the following description taken in connection with the accompanying drawings in which

Figure 1 is a front elevation partly in section of a grand piano embodying features of the present invention with the tone reflectors in partly open position;

Figure 2 is a bottom plan view taken in section on the line 2-2 of Figure 1; and

Figure 3 is a detailed view in section of the control mechanism shown in Figure 2.

Like reference characters refer to like parts in the several figures of the drawings.

In the following description and claims, parts will be identified by specific names for convenience of expression, but they are intended to be as generic in their application to similar parts or equivalent construction as the art will permit.

Referring to the drawings, there is shown a grand piano 10 having for the purpose of producing sound a plurality of tuned strings such as 11 tuned to the notes of the musical

scale. It will be understood that there may be provided for each note of the musical scale one or more of such strings as may be desired. For example in the lower part of 60 the scale a single string may be employed, in the upper part of the scale three strings may be employed for each note, and in an intermediate part of the scale two strings may be employed for each note. The strings 11 are 65 mounted in a usual frame 12 in a conventional manner. This frame 12 together with the strings 11 are located above a sounding board 13. For vibrating the strings of each of the notes of the scale by percussion there 70 is provided a suitable hammer action such as 13' operatively connected to one of the keys 14 respectively of the manual of the piano. The strings are positioned within a casing 75 15 which is mounted on a plurality of feet 16 so that the manual comprising the keys 14 is positioned at a convenient height above the floor. Below the manual and secured to the lower wall of the casing 15 there is provided a pedal block 17 upon which there is positioned a plurality of pedals, which show three in number, as at 18, 19, 20. The two right-hand pedals as seen in Figure 2 designated respectively 19 and 20 are connected to the sostenuto and loud pedal actions of the 80 piano in a conventional manner and have no bearing on the present invention, need not be further described.

The left-hand pedal 18 is pivotally mounted in the block 17 and is operatively connected to a vertically reciprocating rod 21, the upper end of which engages one arm of a pivoted bell crank lever 22. The arrangement is such that when the pedal 18 is depressed by the musician the rod 21 is raised 95 and the bell crank lever 22 is rotated in a counter-clockwise direction as seen in Figure 2.

The opposite arm of the bell-crank lever 22 is pivotally connected by means of a connecting link 23 to a primary valve member 24 slidably mounted within a valve casing 25.

A spring 26 having one end secured to the link 23 and the other end secured to a bracket 27 mounted on a portion of the pedal block 17, is provided for retracting the primary valve member 24, the bell-crank lever 22 and the left-hand pedal 18 to the normal position illustrated in Figure 1.

A secondary slide valve member 28 is positioned immediately adjacent the primary slide valve member 24 and is arranged to re-

2
ciprocate independently thereof and within the casing 25.

The valve casing 25 is provided with an inlet chamber 30 which communicates with a conducting pipe 31 extending from a suitable source of power such as an air pump 32. The pump is driven in any suitable manner, as by a belt 33 and an electric motor 34. The motor 34 is connected to suitable power mains 35.

The primary slide valve member is provided with a valve port 40 in an intermediate portion thereof which communicates with the chamber 30, and is provided with two oppositely disposed passages 41, 42 both of which are in communication with atmosphere. The secondary slide valve member is provided with two spaced ports 43, 44 separated by a partition 45. In one position of the slide valve members 24 and 28 as illustrated in Figure 3 of the drawing, the primary slide valve port 40 is opposite to and closed by the partition 45 of the secondary slide valve member. The ports 43 and 44 are then at atmospheric pressure, being in communication with atmosphere by way of the passages 41 and 42 respectively. The left-hand port 43 communicates with a conducting pipe 46 and thus in turn with the right-hand portion 47 of a double bellows 48, the left-hand portion 49 of which is similarly in communication by way of a conducting pipe 50 with the right-hand port 44. The double bellows 48 is mounted in fixed position on the piano 10, and is provided with a central arm 51, the position of which is determined by the conjoint action of the two halves 47, 49 of the bellows. The outer end of the arm 51 is operatively connected to the secondary slide valve member by means of a pin and slot connection. A link 52 is pivotally connected to the outer end of the secondary slide valve member, and is connected at its outer end with an arm 53 which in turn is secured to a rotatable shaft 54. The shaft 54 is journalled in spaced bearings 55, 56 mounted upon the casing 15 of the piano and extends through the casing to the upper portion of the piano. The shaft 54 is provided with a fixed collar 57 for maintaining the shaft in predetermined longitudinal position with respect to its bearings. An arm 58 is affixed to the shaft below the lower wall of the casing 15 and is pivotally connected at its outer end by a link 59 to one arm of a bell-crank lever 65 pivotally mounted on the piano casing 15, and having its other arm pivotally connected by means of a link 60 to a reciprocating connecting rod 61. Similarly there is secured to the shaft near its upper end an arm 62 the outer end of which is pivotally connected by means of a connecting link 63 to a reciprocating connecting rod 64.

65 The casing 15 of the piano is provided

with oppositely disposed controllable apertures as at 70, 71 and boundary walls 72 intermediate thereof. Mounted in the upper aperture 70 is a series of reflectors as at 73, therefor, serving to control the emission of sound. Each reflector 73 is preferably in the form of an elongated, flat member pivotally mounted to rotate about its longitudinal axis, and is constructed with a layer of sound insulating material for effectively suppressing sound, and an inner face of sound reflecting material such as sheet aluminum or other sheet metal. The intermediate boundary walls 72 of the casing also include a layer of sound absorbing material of felt, wool or grass, and are provided on the inner surface with sound reflecting material.

Each of the reflectors 73 is provided with an arm 75 on its outer face and the outer ends of the arms 75 of the upper series of reflectors are pivotally connected to the upper connecting rod 64. The upper series of reflectors 73 are mounted in the upper aperture 70 and when the upper connecting rod 64 is moved to the right of Figure 1, the upper reflectors effectively close the upper aperture 70. Similarly there is mounted in the lower aperture 71 a second series of reflectors of like construction and adapted to control the emission of sound through the lower aperture. The construction of the lower group of reflectors corresponds to that of the upper group and the outer ends of the arms 75 of the lower group are pivotally connected to the lower connecting rod 61.

In operation the manual of the piano is employed by the musician in the usual way to cause vibration of the strings in accordance with the music being played. In order to produce a desired effect the pedal 18 is depressed to a desired extent. Downward movement of the pedal 18 causes the rod 21 to be moved upwardly so as to rotate the bell crank lever 22 against the tension of the spring 26 in a counter-clockwise direction as seen in Figure 1. The primary slide valve member 24 is thus moved to the left of Figure 1. This causes the port 40 to register with the port 43 thus allowing air to pass from the pump 32 through the tube 31, chamber 30, ports 40, 43, tube 46 to the right hand bellows 47, thus inflating this bellows and causing it to move the arm 51 to the left, the left-hand bellows 49 being at this time exhausted through the tube 50, port 44 and passage 42. As the arm 51 moves to the left, it causes the link 52 also to be moved to the left thus causing rotation of the arm 53 in a counter-clockwise direction as seen in Figure 2. This motion is communicated to the shaft 54 rotation of which causes the arm 58 to be moved also in a counter-clockwise direction. The arm 58 is operatively connected to the bell-crank lever 65 which is also ro-

tated in a counter-clockwise direction and which causes the link 60 to be moved towards the right. The connecting rod 61 is thus moved to the right and thus the reflectors 73 of the lower group of reflectors are rotated in a counterclockwise direction as seen in Fig. 1. Rotation of the shaft 54 also causes the arm 62 to be moved towards the right and this movement is communicated to the connecting rod 64 thus moving the upper group of reflectors 73 in a clockwise direction.

The action just described continues so long as the movement of the pedal 18 downwardly continues as the secondary slide valve member 28 is moved a sufficient amount to cause the partition 45 to be moved towards the port 40. When the movement of the pedal is discontinued the secondary slide valve member 28 is moved into position opposite the port 40 thus shutting off the supply of air to the bellows. During continuous movement of the primary valve member 24 there will of course be a continuous follower movement on the part of the secondary valve member 28, since any movement of the port 40 away from the partition 45 will result in a corresponding movement of the secondary valve member 28. This movement may continue until the pedal 18 has been fully depressed at which time the closures will be entirely closed.

If the pianist desires to open the tone reflectors he relieves the pedal 18 of pressure thus allowing it to be lifted under the action of the spring 26 which will cause the primary slide valve member 24 to be moved to the right thus connecting the pump 32 to the left-hand portion 49 of the bellows and will rotate the shaft 54 and the bell-crank lever 65 in a clockwise direction thus tending to open the tone reflectors.

In this way the pianist can, by a very slight pressure of the foot on the pedal 18, cause by means of the power bellows 47 and 49 a rapid action of the tone reflectors independently of the momentum or weight of the reflectors.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

I claim:

1. In a musical instrument of the percussive type, the combination with an insulated body portion for effectively suppressing the sound produced by the instrument, of means for emitting a desired volume of sound from the instrument, an operating device including a fluid pump for said means, a source of

power for said device, means operatively interconnecting said device and said power source, and a control valve for controlling the flow of fluid from the pump to said device.

70

2. In a musical instrument, a plurality of strings forming a sound source, a plurality of percussion hammers for causing vibration of said strings, a sound insulated casing surrounding said strings and having apertures, reflecting devices rotatably positioned in said apertures for controlling the sound emitted therethrough, a pneumatically operated bellows for actuating said reflecting devices, a pneumatic pump, and a control valve 75 interposed between the pump and the bellows for controlling the operation of the reflectors.

80

3. In a musical stringed instrument, a plurality of strings tuned to the notes of the musical scale, a sounding board adjacent said strings, a substantially sound proof casing having a metal lining and surrounding said board and said strings and forming two enclosed resonating chambers, a plurality 85 of reflecting devices for each of said resonating chambers for controlling the sound emitted therefrom, a pneumatically operated bellows for actuating said reflectors, a pneumatic pump, and a control valve 90 interposed between the pump and the bellows for controlling the operation of the reflectors.

95

4. In a musical instrument, a plurality of strings forming a sound source, a plurality of hammers for causing vibration of said strings, a sound insulated casing surrounding said strings and having apertures, a plurality of centrally pivoted metal lined reflecting devices rotatably positioned in said apertures for controlling the sound emitted therethrough, pneumatic pump means including a two-way pneumatically operated bellows operatively interconnecting the power source and said reflecting devices, a control valve included in said means to control the operation thereof, and a pedal to actuate said controller at the will of an operator.

100

5. In a musical stringed instrument, a plurality of strings tuned to the notes of the musical scale, a sounding board adjacent said strings, a substantially sound proof casing having metal lining and surrounding said board and said strings and forming two enclosed resonating chambers, a plurality 115 of centrally pivoted metal lined reflecting devices for each of said resonating chambers for controlling the sound emitted therefrom, a pneumatically operated two-way bellows for selectively rotating said reflectors in either direction, a pneumatic pump, and a control valve interposed between the pump and the bellows for selectively controlling the movement of the reflectors.

120

6. In a musical instrument, a plurality of

125

130

- strings forming a sound source, means for causing vibration of said strings, a sound insulated casing surrounding said strings and having apertures, a plurality of reflectors rotatably positioned in said apertures forming in one position closures for the apertures, a fluid actuated motor mechanism for moving the reflectors, a fluid pump for operating the motor mechanism, means operatively interconnecting the power source and the motor mechanism, and control valve for controlling the interconnecting means at the will of an operator.
7. In a piano the combination with tuned strings for producing damped compressional waves, a casing therefor, a plurality of tone reflectors rotatably positioned in a wall of the casing, a fluid operated motor for moving said reflectors into desired position, a control valve having a secondary slide valve member operatively connected to said motor mechanism, a pedal, and means operatively interconnecting the primary slide valve member with said pedal.
8. In a musical instrument the combination with a plurality of strings tuned to the notes of the musical scale, means for vibrat-
